United States Patent Office

Des. 185,937

Patented Aug. 18, 1959

185,937

BOX FOR STORING AND DISPLAYING GASKET RINGS OR THE LIKE

Joseph M. Bruening, Cleveland, and Robert C. Vanlew, Rocky River, Ohio, assignors of one-half to E. F. Houghton & Co., Philadelphia, Pa., a corporation of Pennsylvania, and one-half to Bearings, Inc., Cleveland, Ohio, a corporation of Delaware

Application May 16, 1958, Serial No. 50,929

Term of patent 14 years

(Cl. D80—5)

Fig. 1 is a perspective view of a box for storing and displaying gasket rings or the like in open condition;

Fig. 2 is a perspective view showing the top, front and one side of the box;

Fig. 3 is a perspective view showing the top and rear and the other side of the box;

Fig. 4 is a sectional view through the box taken along the line 4—4 of Fig. 2.

Fig. 5 is a fragmentary rear elevational view showing one of the hinges of Fig. 3.

We claim:

The ornamental design for a box for storing and displaying gasket rings or the like, as shown.
